[57] **CLAIM**

The ornamental design for a vehicle interior door lower panel exterior surface with viewing window, as shown and described.

DESCRIPTION

FIG. 1 is a perspective view of a vehicle interior door lower panel exterior surface showing our new design, the opposite side being a mirror image thereof;

FIG. 2 is a front view thereof;

FIG. 3 is a top view thereof;

FIG. 4 is a bottom view thereof;

FIG. 5 is a right side view thereof; and,

FIG. 6 is a left side view.

The dotted line showing of a vehicle door is for illustrative purposes only and forms no part of the claimed design.
